BOOK MARKER

George B. Von Alvensleben, Eureka, Calif.

Application January 15, 1940, Serial No. 313,929

3 Claims. (Cl. 116—119)

My invention relates to improvements in a detachable type book marker.

One of the objects of my invention is to provide a flexible type book marker which can be inserted between the pages of a book and which does not require any separate fastening means to hold it in place.

Another important object of my invention is to shape the book marker in such a way that its natural resiliency holds it securely in place, and yet when it is desired to remove it from between certain pages and place it in another place in the book, the same resiliency permits it to be removed without damage to the structure.

Another important object of my invention is to provide a resiliently formed book marker so that it can be removed without bending the hooks by which it is held to the top and bottom edges of the binding.

A further object of my invention is to provide a book marker which can be manufactured at a low price and which is completely self-contained.

With markers of the prior art, such as in my earlier patent, No. 1,858,605, it has been necessary to provide means for holding the marker in the book. Also, with many of the markers of the prior art of this general type it has been necessary to thread through holes or slots a rubber band or other flexible securing member.

In the accompanying drawing, forming a part of this specification, and in which like numerals are employed to designate like parts throughout the same:

Fig. 1 is a view in perspective showing an opened book having a single marker in place therein;

Fig. 2 is a plan view of a marker with a portion of the book shown in dotted lines;

Fig. 3 is a modified form of the marker;

Fig. 4 is a further modification in form;

Fig. 5 is a still further modification; and

Fig. 6 is still another modification.

In certain uses to which books are put, it is sometimes desirable to have as many as thirty markers placed between as many selected pages of a book. These markers are placed in the books one at a time and sometimes more than one marker is placed between one given pair of pages. It is therefore necessary to provide means for setting the markers in place which will not require the bending of the means which holds them in the book.

In the drawing, B represents a book having the usual covers C and pages P. At the back is the binding N which provides shoulders II at the top

and bottom. These shoulders extend across the full width of the back of the book.

My invention is designed to take advantage of the presence of these shoulders and by using them as an anchoring means, I can dispense with the usual separate securing means heretofore used.

The marker proper comprises the base member 12 having hooks 13 formed at each end to engage the edges or shoulders II of the binding. To the base member or connecting body portion 12 are secured marker or indicia bearing extensions 15 which bear suitable reference numerals. These usually have numerals from 1 to 30 at the ends which project beyond the edges of the pages P.

The important thing about the present invention is that the connecting body portion 12 has a continuous web 16 offset from a substantially straight line 17 connecting the engaging members 13, so as to provide a non-continuous connection or area between the hook members 13. Another way of stating this is as follows: The body portion 16 is cut away from the straight line 17 connecting the hooks 13. The purpose of this is to permit the hooks 13 to be disengaged from the shoulders II without requiring bending of the hooks 13. Pulling on either or both hooks 13 causes a lengthening of the space between the hooks, and this is permitted by the offset connecting body portion 16 which usually bends or twists a little as the hooks 13 are separated. (See dotted lines in Fig. 2.) The natural resiliency of the connecting body member 16 causes the marker to flatten as soon as the hooks 13 are released and they assume their regular spacing in engagement with the shoulders II on the back end of the book. When the book is closed, the leaves hold the connecting body portion 16 flat so that hooks 13 will not separate and become displaced.

When it is realized that there are usually up to 30 of these markers placed in a book not over an inch thick, the facility with which a marker of this present type can be taken out and replaced in the book will be appreciated.

The present invention lends itself to many different shapes for the connecting body portion 16 and it is not intended that the ones illustrated for the purpose of explaining the invention shall be the only ones to be covered by the claims. In Figs. 3 to 5 I have illustrated other forms which the connecting body portion may take.

In Fig. 3, instead of being an arcuate member as in Fig. 2, the connecting body portion is formed by a straight member 20 and right angle

members 21 and 22 connected to the hooks 13. The offset connecting member 20 allows the hooks 13 to be spread apart the distance necessary to place them over the shoulders 11. The natural resiliency of the material used, usually Celluloid or a similar product, will cause the marker to resume its normal flat shape as soon as the user releases the hold on the hooks 13.

In Fig. 4, the connecting body portion 23 is substantially solid except that it will have one or two slits 24 and 25 or even more slits which will give the necessary freedom of movement to hooks 13 when they are pulled by the one using the marker.

In Fig. 5 there is a further modification in which the indicia bearing extension 15 is formed integral with the lower hook 13 and the portion of the connecting body 26. The upper hook 13 and the other portion of the connecting body 27 are joined to body 26 by an offset arm 28 and 30. This gives an unconnected place or slit 31 so that the hooks 13 can be spread apart for insertion or removal from the binding of the book.

From these modifications, as well as from the structures shown in Figs. 1 and 2, it will be seen that the essential thing is for the ends or hooks 13 to be separated further apart as shown in dotted lines in Fig. 2, simply by pulling them apart, which causes the connecting body portion 16 to twist slightly and pull in towards the imaginary dotted line 17.

The amount of offset of distance between the connecting body portion 16 and the imaginary line 17 connecting the hooks can be varied to suit the designer's choice. It is only necessary that it be enough to allow sufficient separation of the hooks 13 for them to be easily applied over the shoulders 11 and 12. The same thing can be said with regard to the slits 24 and 25 in Fig. 4 and 31 in Fig. 5.

In Fig. 6 the marker comprises the base member 40 having hooks 13 formed at each end to en-

gage the edges 11 of the binding. The base member 40 is offset at 41 so as to provide the slit 42 thereby allowing the hooks 13 a range of movement apart. The indicia bearing member 15 may be arranged so that the indicia portion 43 projects from the top of the book. The marker may be made from one or more pieces of material without departing from my invention.

What I claim is:

1. A book marker comprising an elongated normally flat transversely bow-shaped flexible body portion, and inwardly facing opposed hooks carried by and extending divergently beyond the ends of the body portion for engaging the upper and lower edges of a book backing, the hooks being substantially laterally and longitudinally displaced from the body portion for separation thereof from the book backing through transverse flexing of the body portion, toward said book backing.

2. A book marker comprising an elongated normally flat body portion which is bow-shaped in the plane thereof, inwardly facing opposed hooks carried by the ends of the body member and extending in opposite directions beyond the concave edge thereof for engaging the upper and lower edges of a book backing and an indicia bearing extension carried by the bow-shaped body portion and projecting from the convex edge thereof.

3. A book marker comprising a normally flat arcuate body portion in the form of a thin strip of uniform width substantially throughout its arcuate extent, the ends of the arcuate body portion merging into extensions of reduced width and diverging from the concave edge of the body portion, inwardly facing opposed hooks on the ends of the extensions for engaging the upper and lower edges of a book backing, and an indicia bearing extension secured to the body portion and projecting from the convex edge thereof.

GEORGE B. VON ALVENSLEBEN.
